OIL BURNING HEATER HAVING A CONCENTRIC FUEL PAN AND AIR CONE

Jay T. Clark, Milan, Mich.; Eva S. Clark administratrix of said Jay T. Clark, deceased

Application January 22, 1947, Serial No. 723,545

2 Claims. (Cl. 158—91)

1

This invention relates to oil burners of the concentric type, having a central air intake.

An important object of the invention is to provide a burner of the character described which will be unusually efficient in providing a maximum of heat, by reason of the provision of an improved structure for distributing the flames radially away from the burner, thereby quickly and evenly heating the walls of the heating drum of the furnace in which the burner is mounted.

Another important object of the invention is to provide a burner which will fulfill with maximum efficiency the above-stated purpose, but which is nevertheless of unusually simple and novel design, inexpensive of construction, and easily adapted for mounting in well-known types of conventionally constructed furnaces.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

Referring to the drawings

Figure 1 is a view taken on line 1—1 of Figure 2, in which the burner is shown partly in top plan, and partly in horizontal section.

Figure 2 is a view taken on line 2—2 of Figure 1.

Referring to the drawings in detail, an outer casing 5 is provided, that is preferably formed from steel material or the like, and as shown clearly by Figure 2, is of inverted frusto-conical formation, being open at top and bottom. Seated on the upper edge of the outer casing 5 is an annular baffle 6 having a flat portion that extends inwardly a short distance relative to the upper edge of the casing, an upwardly extending inner edge 7, and a depending flange 8 around its outer edge, the flange 8 serving to hold the annular baffle in its proper position of mounting upon the outer casing 5.

To the bottom edge of the outer casing 5 is secured, as by welding, the upwardly extended outer edge of an annular pan 9. As shown particularly by Figure 2, the bottom of the pan 9 is sloped downwardly from the outer edge thereof, the inner portion of the pan surrounding the opening formed therein being extended upwardly from the bottom at a sharp angle thereto.

The pan 9 serves as a receptacle for oil admitted to the burner, and it is seen from the construction of the pan that the oil, when admitted, will flow

2

to the lowermost portion of the bottom, as shown at 10 in Figure 2.

Oil is admitted to the pan 9 by means of a feed pipe 11.

Extended upwardly through the opening in the annular pan 9 is an air cone 12, that is substantially of frusto-conical formation, and which is preferably secured fixedly to the upwardly extended inner edge of the pan 9, as by welding or the like. At its lower end, the air cone 12 communicates with an air intake duct 13 with which it may be formed integrally, and which may be either of the natural or forced draft type.

Referring to Figure 2, it is seen that the upper end of the cone 12 terminates slightly short of the upper edge of the outer casing 5. Removably seated on the open upper end of the cone 12 is a large circular baffle plate or disc 14, that is preferably formed with a downwardly extended center portion 15 that fits into the open upper end of the cone, so as to hold the baffle plate in proper position.

The baffle plate 14 is in diameter smaller than the inner diameter of the annular baffle 6, thus forming an open space therebetween which has been indicated at 16, this comprising a combustion chamber outlet.

From a point slightly above the pan 9, the cone 12 is freely perforated by the provision in the wall thereof of a plurality of rows of spaced openings, these rows being provided up to a point slightly below the upper end of the cone. These openings constitute means whereby air entering the cone from the air intake duct may be emitted from the cone into the annular chamber surrounding the cone, the openings being designated by the reference character 17, and comprising the sole inlet for air into the combustion chamber.

Removably seated in the lower portion of the combustion chamber formed by the outer casing 5 cooperating with the air cone 12 is an annular lower baffle ring 18. This may be formed in sections to permit easy disassembly of the burner structure, which sections, when joined, give the lower baffle its annular form. The outer edge 19 of the lower baffle is positioned against the wall of the outer casing 5, and the inner edge 20 is spaced from the wall of the air cone 12 to provide an annular outlet therebetween for products of combustion. To the lower surface of the lower baffle 18 are secured, by any well-known fastening means 21, vertical baffles 22. These are radially disposed around the air cone 12, and are spaced therefrom, as clearly shown by Figure 2.

The vertical baffles 22 are integrally formed with plates 23 whereby they are secured to the annular lower baffle 18, the baffles proper extending downwardly from said plates in perpendicular relation thereto, and terminating at their lower ends in points 24 that rest on the bottom of the pan 9. Thus, it is seen that the vertical baffles 22 serve not only as baffles, in a manner to be hereinafter described, but also as legs whereby the annular lower baffle 18 may be seated in proper position in the chamber.

In operation of my burner, oil is fed to the pan 9 through the feed pipe 11. An important characteristic of the pan 9 is its unusual adaptability for distributing the fuel evenly around the cone 12, and in a direction toward the wall of the cone. By reason of the construction of the pan, even a very small amount of fuel is spread completely around the cone. It is, of course, understood that the fuel will be delivered to the pan 9 in regulated quantity, this being effected by any of various well-known means not constituting a part of the present invention. The fuel is then ignited electrically, by torch, or by any other well-known means.

As the vaporized oil gas resulting from igniting of the fuel rises, it is mixed with air emitted through the air outlet opening 17 in the cone 12. The annular lower baffle 18 cooperating with the vertical baffles 22 direct the resulting products of combustion through the open space between the inner edge of the baffle 18 and the wall of the cone 12. The heat so directed against the cone increases the draft through the cone, resulting in maximum efficiency in combustion.

As the heat-expanded products of combustion are fed through this open space, maximum efficiency as to further expansion thereof is provided by the diverging upper walls of the cone 12 and lower casing 5.

The formation of the circular baffle plate 14, and its positioning slightly below the annular baffle 6 results in the flames being channeled through the open space 16 therebetween, and being directed against the walls of the drum of the furnace in which the burner is mounted, thus resulting in maximum heating of the walls of said drum.

It is pointed out that by reason of the particular shape and arrangement of the parts of my burner, oil fed thereto will burn cleanly and with maximum heat regardless of the quantity of said oil. Even a very small amount of oil will be properly burned, as hereinbefore described. The angle of the wall of the cone 12, further, is particularly designed to direct the flow of the products of combustion directly on the heated baffle plates 14 and 18, thus increasing the vaporizing effect of the products of combustion. In addition, the formation and arrangement of the annular lower baffle 18 permits a shortening of the generating time of the products of combustion. Co-

operating with the baffle 18 in this respect are the vertical baffles 22, which assist in maintaining proper combustion as the fuel approaches exhaustion as for instance, when the fuel tank becomes empty, and this prevents fouling of the burner from carbon.

What is claimed is:

1. An oil burner, comprising an outer casing of inverted frusto-conical formation, a fuel-receiving annular pan extending from the lower edge thereof and provided with a relatively large central opening, the bottom of said pan being sloped downwardly from the casing, an annular baffle mounted on the upper edge of the casing and extending inwardly therefrom a short distance, a perforated air cone of frusto-conical formation upwardly extended through the opening in the pan, a circular baffle plate removably seated on the top of the air cone, spaced vertical baffles extending upwardly from the bottom of the pan and disposed radially of the cone, and an annular lower baffle mounted on the vertical baffles and disposed approximately horizontally.

2. An oil burner, comprising an outer casing, of inverted frusto-conical formation, a fuel-receiving annular pan extending inwardly from the lower end thereof, and provided with a relatively large central opening, the bottom of said pan being sloped downwardly from the casing, an annular baffle mounted on the upper end of the casing and extending inwardly therefrom a short distance, a perforated air cone of frusto-conical formation upwardly extended through the opening in the pan, the upper end of the cone terminating a short distance below the upper end of the casing, a circular baffle plate removably seated on the top of the air cone, said baffle plate being smaller in diameter than the diameter of the inner edge of the annular baffle, providing an open space therebetween, spaced vertical baffles extending upwardly from the bottom of the pan and disposed radially of the air cone, and an approximately horizontal annular lower baffle mounted on the vertical baffles and spaced from the air cone.
